Thomas J. Donnelly
ATTORNEY.

UNITED STATES PATENT OFFICE

2,096,372

SHOE PRESSING APPARATUS

Louis A. Colella, Detroit, Mich., assignor of one-third to Marie Schell and one-third to Marshall G. Pearce, Detroit, Mich.

Application April 27, 1932, Serial No. 607,816

4 Claims. (Cl. 12—33)

My invention relates to a new and useful improvement in a shoe pressing apparatus adapted primarily for use in shoe repairing, although from the description of the invention its utility for shoe building will also appear. In shoe repairing, as now practiced, it is quite customary to attach a sole or a half-sole to the shoe by means of glue or other similar adhesives. At the present time it is difficult to properly secure a sole to a shoe because of the lack of any means for pressing the welt of the shoe firmly against the outer edges of the sole. It is an object of the present invention to overcome this difficulty and avoid this objectionable feature by providing a construction wherein the welt of the shoe will be securely engaged and pressed against the sole to be affixed thereto, while the remainder of the sole is firmly pressed against the shoe.

It is another object of the present invention to provide a means for pressing the welt of a shoe against a sole to be attached thereto and heating the welt during the pressing operation.

It is another object of the invention to provide a device of this class which will be simple in structure, economical in manufacture, durable, highly efficient in use, and easily and quickly applied for use.

Other objects will appear hereinafter.

The invention consists in the combination and arrangement of parts hereinafter described and claimed.

The invention will be best understood by a reference to the accompanying drawings which form a part of this specification and in which,

Fig. 1 is a central, vertical, sectional view of the invention, with parts broken away and parts shown in side elevation.

Fig. 2 is a fragmentary, top-plan view with parts broken away.

Fig. 3 is a sectional view taken on line 3—3 of Fig. 1.

Fig. 4 is a fragmentary sectional view taken on line 4—4 of Fig. 1.

Fig. 5 is a fragmentary side elevation view illustrating a hinge on the presser member.

Fig. 6 is a top-plan view of a modified form of the invention.

Fig. 7 is a side elevation view of the modified form of the invention.

Fig. 8 is a top-plan view of a further modified form of the invention.

Fig. 9 is a fragmentary, sectional view, taken on line 9—9 of Fig. 6.

In the invention I use a presser bed 12, having a metallic network supporting member 13 se-

cured thereto, and supporting a layer of yieldable material 14 such as felt or the like, covered by a cover 15, of leather or similar material, held in position by the retaining band 16. This bed 12 is supported on a suitable support 17. The shoe 18, to which it is desired to attach the sole 19, is pressed by a suitable last section 20 and a last section 21, having a heating element 22 therein. The last section 20 is provided with a shank 23 against which a suitable pressing screw 24 is attached to engage for pressing the shoe on the presser bed.

A supporting arm or bracket 25 extends outwardly from the shank 23 and threaded through the arm 25 is a screw 26 on which is mounted a hand wheel 27. The lower end of the screw 26 is swivelly connected to the head 28 of the supporting rib 29. This supporting rib 29 is provided at its opposite sides with the recesses 30 and 31. A longitudinally extending slot 32 is formed in each of the recesses and riding in the slots 32 are bolts 33 and 34. The bolt 33 serves to connect a brace arm 35 to the frame and to the rib 29. This brace arm 35 connects by means of the set screw 36 to the welt-engaging frame 37. This welt-engaging frame is provided with the swingable section 38, hinged as at 39. Secured to the swingable section 38 is a brace arm 40, having a bifurcated end 41 attached for embracing one of the bolts 34. The lower end of the brace arm 40 is secured by the stud 42 to the section 38. This connection of the brace arms 35 and 40 with the welt-engaging member for the same connection is made between the lower end of the rib 29 and the welt-engaging member, or frame 37. In this type of construction there is threaded through the rib 29 a stud 44, which is swivelly connected to the welt-pressing frame 37 and provided with a wing nut 45 which is fixedly mounted on the stud 44 so that upon a thread of the stud 44 the welt-pressing member 37 may be forced inwardly of the shoe so as to engage the entire surface of the welt. It will be noted that the inner face 46 of this welt-pressing member is concave to permit entry of the presser member inwardly, so as to engage the entire surface of the welt. Downward pressure on this presser-frame is exerted through the rib 29 the braces 35 and 40 and the screw 26. Each of the bolts 33 and 34 is provided with a wing nut 47, so that the position of the brace rods 35 and 40 relative to the slots 32 may be determined by adjusting the position of the brace rods by means 55

of bolts 33 and 34 and thus the shape of the presser frame may be determined and its size regulated so that it may be accommodated to shoes of various sizes and general shape.

5 With a device constructed in this manner, it is obvious that the welt of the shoe may be always retained firmly pressed against the outer edge of the sole, so that a secure affixing of the sole to the welt is assured.

10 In Fig. 6, I have shown a modified form of structure in which the welt-pressing member is flexible, formed from a resilient sheathing 48, in which is extended the section rods 49. The rib 29' is connected pivotally at one end of the brace rods 35' and 40'. The other ends of these brace rods are looped, as at 50, to embrace the welt-presser member and the lower end of the rib 29' is also looped, as at 51, about the presser member.

20 In Fig. 8, I have shown the presser-member formed from a forward section 52, having a pair of side sections 53 hingedly connected thereto.

It is believed obvious that an electrical heating element may be extended through the presser member if desired, and, in Fig. 1 I have shown the presser-member 37 with a heating element 54 embedded therein.

25 In the form shown in Figs. 6, 7, and 8 greater flexibility is present than in the form of presser-members shown in Fig. 2; but the general operation and effect of all of the forms of presser-members is the same.

30 While I have illustrated and described the preferred form of construction, I do not wish to limit myself to the precise details of structure shown, but I wish to avail myself of such variations and modifications as come within the scope of the appended claims.

35 Having thus described my invention, what I claim as new and desire to secure by Letters Patent is:

1. In a device of the class described: a supporting member having grooves formed on its opposite faces adjacent one end; a welt engaging member secured to the opposite end of said supporting member, said welt engaging member comprising a pair of oppositely disposed, relatively movable parts; a brace member connected at one end to each of said parts and engaging at its opposite end in said groove; and means carried by said supporting member for adjusting 5 the positions of said ends in said grooves.

2. In a device of the class described: a welt engaging member having a pair of oppositely disposed, relatively movable parts; a supporting member connected at one end to said welt engaging member, and overlying the same between said relatively movable parts; a pair of arms each projecting outwardly from the free end of said supporting member and connected to one of said movable parts; and means for adjusting 15 20 said connecting arms relatively to said supporting member for moving said parts relatively to each other for accommodating the same to shoes of various sizes and shapes.

3. A welt engaging member comprising: a pair 25 of oppositely disposed relatively movable welt engaging parts for engaging the welt of a sole throughout its length; and an electric heating element extending longitudinally of each of said parts.

4. In a device of the class described, a welt engaging member comprising a plurality of welt engaging parts swingably connected at adjacent ends; means for swinging said parts relatively to each other for adjusting the size of said member; and a flexible heating element extending around said member and swingable with said parts.

LOUIS A. COLELLA. 40
